UNITED STATES PATENT OFFICE.

PETER FRANTZ, OF STERLING, ILLINOIS, ASSIGNOR TO FRANTZ MANUFACTURING CO.,
OF STERLING, ILLINOIS, A CORPORATION OF ILLINOIS.

DOOR-HANGER TRACK.

1,329,460.

Specification of Letters Patent.

Patented Feb. 3, 1920.

Application filed April 17, 1916. Serial No. 91,529.

To all whom it may concern:

Be it known that I, PETER FRANTZ, a citizen of the United States of America, and resident of Sterling, Whiteside county, Illinois, have invented a certain new and useful Improvement in Door-Hanger Tracks, of which the following is a specification.

In the construction of door-hanger-tracks, it has heretofore been the practice, in some cases, to construct the track and housing from sections which are arranged end to end, and which are held in this position by brackets which have their upper end portions secured to the building and which are bent to conform to the outer surface of the track. The said track sections have usually been made from heavy sheet-metal, and the brackets are each formed from a separate piece of metal. The said brackets have usually been arranged at the ends of the sections, so that each bracket would cover or conceal the butt-joint between adjacent sections. These brackets were considered necessary, moreover, to stiffen the housing against sagging under the weight of the door.

The object of my invention is, therefore, to provide an improved construction whereby the said brackets are not necessary, and of such character that the sections of the track overlap one upon the other, the overlapping end portion of each section serving as a substitute for the bracket previously employed for this purpose, thereby stiffening the housing against sagging under the weight of the door, and obviating the necessity of using said brackets.

It is also an object to provide certain details and features of construction and combinations tending to increase the general efficiency and desirability of a sectional door-hanger-track of this particular character.

To these and other useful ends, my invention consists in matters hereinafter set forth and claimed.

In the accompanying drawings:—

Figure 1 is a cross-section of a door-hanger-track embodying the principles of my invention, the upper portion thereof being broken away for convenience of illustration, and the hanger itself and adjacent portions of the building and the door being also shown.

Fig. 2 is an inside elevation of the said

track, on a larger scale, showing one of the lap-joints by which the sections of the track are connected together.

Fig. 3 is a vertical section on line 3—3 in Fig. 2.

Fig. 4 is a horizontal section on line 4—4 in Fig. 2.

As thus illustrated, my invention comprises a track and housing composed of a plurality of sheet-metal sections arranged end to end, each section having an end portion A at one end thereof, and each section having an end portion B at the other end thereof. In cross-section, the track housing has a vertical web 1, an inclined web 2 joined to said vertical web, a lower vertical web 3 which depends from the outer edge of the said inclined web, and an outwardly inclined lower flange 4, whereby the housing thus formed will readily shed water. The track itself is formed by a trough-shaped section of metal 5 which is suitably secured to the inner surface of the web 3, thus providing a groove for the wheel 6 of the hanger, which latter may be of any suitable or desired character. The end portion A of each section is perfectly straight clear to its edge a, which latter is the vertical end edge of the section. The track 5 at this end of the section is cut off straight, except for a tongue 7 which projects a distance toward the edge a, it being observed that the end edge 8 of the track 5 is a distance back from the said edge a, and that the said tongue is in the horizontal plane of the rivets 9 by which the track is secured to the housing. The end portion B of each section is perfectly straight until it reaches the shoulder b, which latter is opposed to the edge a, being either directly in contact therewith or spaced a slight distance therefrom (as shown in the drawings) to suit the requirements. From this shoulder b, the end portion B then extends outside of the end portion A, the overlapping portion 10 serving as a sort of reinforce or integral bracket to cover the joint between the two sections. On the end portion B, the track 5 has its end portion extended beyond the shoulder b to overlap the edge a of the other section, and extends far enough to engage the edge 8 of the other track section. Also, this overlapping portion 11 of the track is provided with a notch 12 to receive the tongue 7, and as this tongue-and-groove joint between the

two sections of the track 5 is in a vertical plane, it follows that the two track sections are held against relative displacement by the weight of the door. The overlapping of the 5 inner surface of the end portion A by the portion 11 of the track serves to prevent the outer overlapping portion 10 from being sprung outwardly, away from the end portion A, as the end portion 12 of the latter 10 is held tightly between the portions 10 and 11, in the manner shown more clearly in Fig. 4, thus securely holding the end portions of the two track sections against relative displacement, and preventing the lap- 15 joints of the housing from spreading. The portion 10 is provided near its upper end with an opening 13, and the web 1 of the end portion A of the track is provided with a corresponding opening 14, the two openings 20 being in alinement, and through these openings (which are provided for each joint), screws or bolts are inserted to support the track on the building.

With the foregoing construction, it will 25 be seen that sheet-metal track-sections are arranged end to end, in correct alinement with each other, thereby to provide what is practically a continuous housing and track for the door-hangers, but without the necessity of using supporting brackets which are 30 formed from separate pieces of metal. Instead of using such brackets or hangers, the overlapping portions 10 are provided to reinforce and cover the joints between the 35 sections, so that in assembling the track all that is necessary is simply to secure the sections in place, with their adjacent ends properly adjusted relative to each other. In other words, the housing sections and the 40 bolts or screws constitute the entire track structure, and nothing else is necessary in order to install the track for use, notwithstanding that the weight of the door is sustained by the housing. For, with the track 45 supported by the lap-joints of the housing, the door is carried by the housing without danger of sagging.

With the construction shown and described, involving the rivets 9 arranged at 50 opposite sides of the lap-joint in the housing, below the supporting bolt which extends through the openings 13 and 14, and with the ends of the track-sections 5 arranged to interlock, the door is strongly 55 supported by the lap-joints of the housing, and said lap-joints are prevented from spreading under the strains imposed thereon by the weight and movements of the door.

I do not, of course, limit myself to the 60 exact construction shown and described.

It will be further observed that each housing and its track-section can be secured together or assembled at the factory before shipping, and as each track-section is arranged on its housing-section with one end

projecting beyond the shoulder b, to form a pocket for the reception of the straight edge of the adjacent housing-section, the sections, after reaching their places of installation, can be easily mounted without the 70 assistance of expert mechanics or special tools. In other words, the joints between the sections are simply slip joints and the sections are only fastened to the support by bolts or screws at their upper edges, the free 75 edges being locked against displacement, both vertically and horizontally, by the interlocked ends of the track-sections and the slip joint pocket, respectively. This forms a strong, perfectly-aligned construction having the track mounted and supported solely 80 on the housing sections, and provides a construction wherein the expert labor is performed at the factory, so that the track and housing sections can be installed simultaneously 85 on the support, each track-section being attached separately to its housing section.

It will be further observed that by thus lapping the ends of the housing to form the 90 supporting and stiffening member thereof, the stiffening member is not only an integral part of the combined housing and track-support, but also conforms to the hood-like shape thereof. Another feature is that this 95 integral reinforcing or stiffening member lies on the outside of the combined housing and track-support, the offset at b serving to accomplish this, whereby the inner face of the combined track-support and housing 100 is left continuous, all the joints being flush so that the track member 5 may be riveted thereto without being grooved or otherwise bent, thereby contributing to simplicity of construction as well as rigidity.

The sections are secured together in any suitable manner, as by bolts which extend through the lap-joints at 13 and 14, which rigidly secure the structure to the building.

What I claim as my invention is:—

1. In a structure for supporting sliding doors, a plurality of sheet-metal housing-sections, a track on said housing-sections, and a hanger traveling on said track, the ends of said sections being lapped one upon the other and secured together to provide a lap-joint between adjacent sections, thereby to stiffen the housing against sagging under the weight of the door, and so that the housing sections are in themselves sufficient 115 to support said track, the lap-joint having provisions at the upper end thereof for securing the housing to a building.

2. The structure of claim 1, in which said track is composed of sections disposed end 125 to end on the inner surface of said housing.

3. The structure of claim 1, in which said track provides a means to prevent spreading of the lap-joint.

4. The structure of claim 1, in which said 130

track is composed of sections held in alinement and connected together only through the medium of said housing, said track-sections inter-locking at the inner side of the 5 lap-joint to prevent relative up-and-down movement between the ends thereof and to prevent the two thicknesses of the lap-joint from spreading apart.

5. In a device of the class set forth, a 10 combined housing and track to inclose and support the hangers of a door consisting of sheet metal sections secured together and bent longitudinally into the desired shape, and having transverse integral reinforcing 15 members provided at intervals along the length thereof to support the housing and track, these members following the cross-sectional shape of the sheet metal sections and providing the stiffness necessary for 20 supporting the door.

6. The structure of claim 5, said transverse stiffening members being positioned at each of the joints of the sheet metal sections and being formed by overlapping the 25 adjacent ends thereof, means being provided for fastening the upper overlapped portions of the sheet metal sections together, and a track member rigidly fastened along the lower portion of the housing on the inner 30 surface thereof by rivets inserted at each side of each member, so that the lower portions of the housing sections are held in alinement.

7. The structure of claim 5, said transverse stiffening members being positioned at 35 each of the joints of the sections and being formed by offsetting and overlapping the adjacent ends of the sections, the overlap being on the exterior of the housing and 40 the offset being equal to the thickness of the sheet metal, whereby the track-receiving inner surface of the housing is free of projections, and so that the track is against the inner surface of the housing between the 45 joints, this track extending across the joints between the sections thereof to thereby hold the sections in alinement and to keep the overlapped portions in tight contact.

8. In a door hanger track and housing, 50 the combination of (1) sheet metal housing sections provided with overlapping ends, (2) a sectional track on the inner surface thereof having joints between the abutting ends of the track-sections, each joint being 55 disposed on the inner thickness of the adjacent overlap to keep the housing sections

in alinement, and provided with means to hold the track-sections in horizontal alinement, and (3) a door hanger on said track to support the door on the housing. 60

9. In a door hanger track and housing, the combination of sheet metal housing sections provided with overlapping ends, a sectional track on the inner surface thereof having joints between the abutting ends of 65 the track-sections, each joint being disposed on the inner thickness of the adjacent overlap to keep the housing sections in alinement, and provided with means to hold the track-sections in horizontal alinement, said 70 means comprising a tongue and groove for each joint to hold the abutting ends of the track-sections against relative displacement vertically, and a door hanger on said track to support the door on the housing. 75

10. In a door hanger track and housing, the combination of (1) sheet metal housing sections provided with overlapping ends, (2) a sectional track on the inner surface thereof having joints between the abutting 80 ends of the track-sections, each joint being disposed on the inner thickness of the adjacent overlap to keep the housing sections in alinement, and provided with means to hold the track-sections in horizontal alinement, and (3) a door hanger on said track to support the door on the housing, each 85 housing section being offset outwardly at one end thereof to form the overlap and to in effect provide a flat inner surface upon 90 which to secure said track.

11. In a door hanger track and housing, the combination of sheet metal housing sections provided with overlapping ends, the upper end portions of each overlap being 95 perforated through the two thicknesses thereof to receive a device to hold the two housing sections against endwise relative displacement and to support the housing in position, a sectional track on the inner surface thereof having joints between the abutting ends of the track-sections, each joint being disposed on the inner thickness of the adjacent overlap to keep the housing sections in alinement, and provided with a 100 tongue and groove at each joint to hold the track-sections in horizontal alinement, and a door hanger on said track to support the door on the housing. 105

Signed by me at Sterling, Ill., this sixth 110 day of April, 1916.

PETER FRANTZ.
